UNITED STATES PATENT OFFICE.

PHILO J. LOCKWOOD, OF WASHINGTON, DISTRICT OF COLUMBIA.

LUBRICATOR.

SPECIFICATION forming part of Letters Patent No. 781,891, dated February 7, 1905.

Application filed October 14, 1903. Serial No. 177,063.

To all whom it may concern:

Be it known that I, PHILO J. LOCKWOOD, a citizen of the United States, residing at Washington, in the District of Columbia, have invented certain new and useful Improvements in Lubricators, of which the following is a specification.

My invention relates to that class of lubricators in which a body of oil is forced to the part to be lubricated by the action of a reciprocating piston; and my invention has for its object to insure a positive feed and prevent the straining and breaking and disabling of the apparatus which results in constructions heretofore used, and to this end I construct the apparatus as fully set forth hereinafter and as illustrated in the accompanying drawings, in which—

Figure 1 is a longitudinal section of an apparatus embodying my invention. Fig. 2 is a plan view; Fig. 3, a detached view showing the ratchet and pawls.

Upon a suitable framework A is mounted a cylinder B, which in practice has a bore of very small diameter, to which is fitted a plunger or piston C, the cylinder-head being properly packed at the end through which the plunger passes, while at the opposite end there is provided a chamber 1, that communicates with an inlet-port 2 and an outlet-port 3 at a point beyond that reached by the plunger at the limit of its inward movement, a screw-plug 6 closing this chamber in line with the bore, so as to permit access to the chamber and bore for cleaning when necessary. The inlet-port 2 communicates with a reservoir or other source of oil-supply E through a passage controlled by a suitable valve 5, shown as a check-valve, which opens readily when the plunger is drawn outward or is closed under pressure in the chamber 1, while the outlet-port 3 is in communication through a pipe 7 with the steam-supply pipe 8 of an engine or with any other conduit or part to be oiled, a valve 4, shown as a check-valve, seating against back pressure from the pipe 8, but opening under pressure in the chamber 1.

Suitable means are provided for imparting a positive outward movement to the plunger. As shown, a ratchet-wheel 9, turning in a bear-

ing on the frame, carries a cam 10, having an abrupt shoulder, which cam bears against a roller projection 12, carried by the plunger C, which is pressed inward under the action of a spring D, that is connected at one end to a boss at the end of the plunger and at the other end to a projection on the frame, so that when the shoulder of the cam 10 leaves the projection 12 the spring will throw the plunger inward. Any suitable means is employed for imparting a step-by-step movement to the ratchet 9—as, for instance, a pawl 13, connected to a crank-arm 14 of a crank-shaft 15, another arm, 16, of which is connected to any suitable moving part of the machine to be oiled. A spring-pawl 17 below the ratchet-wheel prevents any back movement of the same.

By the above-described arrangement of parts the oil is drawn from the reservoir E into the chamber 1, the valve 5 lifting to permit its passage, and is then forced from the chamber 1, lifting the valve 4 into the pipe 7, and to the part to be oiled. It will be seen that the outward movement of the plunger is slow and positive, affording ample time for the oil to flow into the chamber 1 without the production of a vacuum, which would be apt to occur in feeding heavy oils if the outward movement was instantaneous. This insures normally the full supply of oil to the cylinder B at each outward movement of the plunger. When the shoulder of the cam leaves the projection 12, the inward movement of the plunger is effected through the medium of the spring D, and the oil will be ejected as fast as it can flow through the orifices under the action of the spring.

It will be seen that there can be no straining or pounding of the parts under either of the actions of the piston, such as is apt to occur in that class of apparatus where the inlet and outlet ports do not have constant communication with each other through the medium of an intervening channel or chamber or where the outlet is closed by the plunger when inward, and that it is impossible in the construction shown and in consequence of the presence of this continuous communication of the chamber 1 and outlet-port for the

movement of the plunger to be resisted by a body of oil confined in a chamber having no outlet, as occurs in prior constructions. It will also be seen that if the outlet-pipe 7 should 5 be clogged or obstructed, as may sometimes occur, the plunger is still prevented from being positively forced against an incompressible body of oil, because the spring D in such case, which imparts the inward movement, 10 will yield to such pressure and the plunger will be held from moving without straining or breaking any of the parts, and while the outward movement of the plunger is positive it will be seen that the only effect that can 15 result in the case of the clogging of the supply-pipe would be the production of a partial vacuum in the chamber 1.

While the chamber 1 should be in continuous communication with the cylinder, it should 20 be of limited volume, the valves being arranged as close to the chamber as possible. This is because a large chamber would contain a body of air which might so expand or condense under the movements of the plunger as to fail to exert sufficient force to lift 25 the valves, (no oil flowing in such case,) especially in cold weather and with the heavy oil which it is desirable to use.

It will be evident that the cam and spring

may be differently arranged and of a different character from that shown and that any suitable means for imparting movement to the cam or the plunger C from the operations of the apparatus to be oiled may be employed.

Without limiting myself to the precise construction and arrangement of parts shown, I claim as my invention—

The combination with a steam-pipe, and oil-receptacle of a lubricator having a cylinder, a packing-box at one end, a plunger extending through the said packing-box, inlet and outlet ports and valves, the inlet-port communicating with the oil-receptacle and the outlet-port with the steam-pipe, a spring connected with the plunger to throw it inward, 45 a cam and means for revolving it about the plunger, a bearing on the plunger maintained in contact with the cam by the spring, and a ratchet-wheel and pawl for revolving the cam, substantially as set forth.

In testimony whereof I have signed my name to this specification in the presence of two subscribing witnesses.

PHILO J. LOCKWOOD.
